UNITED STATES PATENT OFFICE.

FINLAY R. McQUEEN, OF MINNEAPOLIS, MINNESOTA.

STORAGE-BIN.

No. 896,233.

Specification of Letters Patent.

Patented Aug. 18, 1908.

Application filed June 20, 1907. Serial No. 379,865.

To all whom it may concern:

Be it known that I, FINLAY R. McQUEEN, a citizen of the United States, residing at Minneapolis, in the county of Hennepin and State of Minnesota, have invented certain new and useful Improvements in Storage-Bins; and I do hereby declare the following to be a full, clear, and exact description of the invention, such as will enable others skilled in the art to which it appertains to make and use the same.

My invention relates to so-called "working" elevators, to-wit, that type of elevator in which grain is not only adapted to be stored, but is adapted to be weighed, cleaned, graded or otherwise worked. In this type of elevator a workhouse is located below the storage bins.

Particularly, this invention relates to fire-proof elevator construction in which masonry work is reinforced with steel or iron.

The invention consists of the novel devices and combinations of devices hereinafter described and defined in the claims.

In the accompanying drawings which illustrate the invention, like characters indicate like parts throughout the several views.

Referring to the drawings, Figure 1 is a vertical section with some parts left in full, taken through the workhouse, the bin compartment, the tower and the car shed of an elevator structure embodying my invention. Fig. 2 is an enlarged section on the same line as Fig. 1, showing the workhouse structure and portions of the bin. Fig. 3 is a plan view of the bin structure, with some parts broken away. Fig. 4 is a section taken on the irregular line $x^4 x^4$ of Fig. 3. Fig. 5 is a section taken on the line $x^5 x^5$ of Fig. 4; and Fig. 6 is a horizontal section taken on the line $x^6 x^6$ of Fig. 4, looking upward.

The storage bins 1 are cylindrical with conical bottoms having discharge passages 2 that open through a reinforced floor 3. These bins are of masonry and may be either monolithic reinforced concrete or of reinforced brick or tile, and they are placed in parallel rows in two directions and are closely positioned so that their tangentially abutting portions are united by metal reinforced vertically extended connecting bodies of masonry 4 which, as will presently appear, constitute extensions or upward continuations of the bin supporting columns and serve to rigidly tie together the adjacent bins.

The bin supporting floor 3 is preferably of

monolithic concrete having formed as part thereof metal reinforced girders 5 and 6 that intersect each other at a right angle. At their points of intersection, the girders 5 and 6 unite with the upper ends of heavy metal reinforced columns 7, preferably of concrete, and the lower ends of which terminate in heavy footings 7^a which, as shown, rest upon a heavy concrete basement floor 8 below which, when required, piles (not shown) may be driven. These columns 7 are located directly in line one with each of the column extensions 4. As shown, they are reinforced by longitudinally extended rods 9 and hoops 10. As best shown in Fig. 4, the upper ends of the columns 7 are expanded at 7^a so that they directly support and unite with quite large areas of the floor 3. The space under the bins is inclosed by side walls 11, preferably of concrete or other masonry, and this space is divided into a workhouse 12 and basement 13 by a suitable workhouse floor 14 shown as made up of transversely extended I-beams and a suitable flooring, the said I-beams being supported by the columns 7 and walls 11. The bin space is inclosed by walls 11^a that constitute extensions of the walls 11.

The tower 15, which is preferably constructed entirely of metal, is located above the bins 1. Its side walls comprises vertically extended iron or steel beams 16 which may be extended downward through the inclosing walls 11^a to the upper portions of the masonry walls 11. Its floors 17 and roof 18 are supported by these wall columns 16 and by interior columns 19, which latter columns are also steel or iron. These interior columns 19 align vertically each with a column 7 and column extension 4, and their lower ends are directly anchored in or bear upon the upper ends of the latter. With this arrangement, the main weight of the machine and other load within the tower and of the tower itself is transmitted directly through the column extension 4 of the bin structure to the main supporting column 7 without adding weight to or putting additional strain upon the bins proper. Furthermore, by the arrangement of the columns 7 and column extensions 4, the bins are reinforced and strengthened and are supported at their strongest portions by the said columns 7.

As in my prior application S. N. 317,317, filed May 17, 1906, entitled grain storage elevators, supplemental storage compart-

ments 20 are formed between each four adjacent bins, and certain of these supplemental storage compartments are provided with transverse masonry tie walls 21 that extend 5 from top to bottom of the bin and cut off from the supplemental storage compartment a vertically extended space through which one of the elevator legs 22 is passed. The coöperating elevator leg is extended through a similar protected passage formed by a masonry tie wall 23 which connects the outer portions of two adjacent bins. The supplemental storage compartments are shown as provided in their bottoms with discharge 15 passages 20^a that open through the floor 3. Within the tower 16 is the usual garner 24, scale 25 and distributing spout 26.

The numeral 27 indicates discharge spouts of the usual or any suitable construction 20 which extend from the tower into a car shed 28 at one side of the workhouse.

The numeral 29 indicates, diagrammatically, box cars within the shed 28.

As shown in the drawings, a grain unloading sink of the kind disclosed and claimed in my prior patent No. 854,377, of date May 21, 1907, entitled "Grain unloading sinks for elevators", and which device, therefore, need not be here described, is applied in the 26 pit 30 below the said car shed.

What I claim is:

1. The combination with a multiplicity of masonry bins having their axes arranged in rows in two directions and having their 35 tangentially engaged sides rigidly united by masonry body portions, certain of which constitute column extensions, and supporting columns below said bins vertically alined and united with said tangential column extension portions of said bins and serving to support the said bins only at two diametrically opposite points, substantially as described.

2. The combination with a multiplicity of

bins having their axes arranged in rows in two directions and on lines that intersect 45 each other approximately at a right angle and having tangentially engaging sides united by vertically extended masonry body portions, certain of which constitute column extensions, supporting columns below said bins, vertically alined and united with said tangential column extension portions of said bins and supporting said bins at two diametrically opposite points only, and certain of which bins are further connected by transverse tie walls that extend from top to bottom of said bins and form, on opposite sides of the tangentially connected portions of the bins, spaces through which elevator legs may be passed, substantially as described. 60

3. The combination with a multiplicity of masonry bins having their axes arranged in rows in two directions and on lines that intersect approximately at a right angle, said bins having their tangentially engaged sides 65 united by said masonry body portions, certain of which constitute column extensions, transversely intersecting metal reinforced concrete or masonry girders located below said bins, certain thereof being extended directly under and united with the tangential column extension forming portions thereof, and metal reinforced concrete or masonry columns below said bins united at their upper ends to said girders and to the said bins 70 at points vertically below the joining portions of said girders and column extension portions of the bins, the said columns supporting said bins at two diametrically opposite points only, substantially as described. 75

In testimony whereof I affix my signature in presence of two witnesses.

FINLAY R. McQUEEN.
